(57) **CLAIM**

The ornamental design for a point sensor, substantially as shown and described.

DESCRIPTION

FIG. 1 is a front elevation view of a point sensor;

FIG. 2 is a back elevation view thereof;

FIG. 3 is a left-side view thereof;

FIG. 4 is a right-side view thereof;

FIG. 5 is a top view thereof;

FIG. 6 is a bottom view thereof;

FIG. 7 is a perspective view thereof; and,

FIG. 8 is a perspective view thereof.

The portions of the drawings shown in broken lines form no part of the claimed design.
